UNITED STATES PATENT OFFICE.

ALBERT W. ALBRECHT, OF UNIVERSITY CITY, MISSOURI.

CENTRIFUGAL PUMP.

Application filed August 18, 1924. Serial No. 732,840.

This invention relates to improvements in centrifugal pumps, and consists in the novel construction hereinafter disclosed.

An object of the invention is to provide a centrifugal pump with a baffle plate adjustably supported adjacent to the outlet from the pump, and means for supporting the baffle plate in selected adjustments with respect to the rotor to regulate the over-throw of the liquid about the rotor.

Additional advantages of the construction will be apparent from the following detailed description taken in connection with the accompanying drawings, in which:

15 Fig. 1 is an end elevation shown on the line 1—1 of Fig. 4.

Fig. 2 is a cross section through the pump taken substantially on the line 2—2 of Fig. 4.

20 Fig. 3 is a cross section taken substantially on the line 3—3 of Fig. 1.

Fig. 4 is a front elevation of the pump, portions being broken away to show the main shaft bearings and lubricating system 25 therefor.

Fig. 5 is a section on the line 5—5 of Fig. 4.

Fig. 6 is a section on the line 6—6 of Fig. 4.

30 In the embodiment of the invention illustrated in the drawing the pump is shown as mounted on a base comprising parallel arranged I-beams 1 which support the pump housing and the bearings for the main shaft.

35 The stator of the pump housing comprises the substantially cylindrical casting 2 which is equipped with integrally cast supporting brackets 3 bolted to the supporting members 1. The casting 2 has integrally formed and 40 downwardly extending annular flanges 4 to which end plates 5 and 6 are secured by bolts 7.

Axially located with respect to the end plate 5 and bolted thereto by bolts 8 is a flanged inlet fitting 9 to which the pump supply or suction pipe is connected. The inner periphery of the pump housing has sectional steel liner plates 10 secured thereto, said liner plates covering the inner surface of the periphery wall and extending upwardly against the inner surface of the outlet conduit 11 which is integrally cast with the housing.

50 The stator is equipped with a block 12 the outer face of which matches the inner peripheral wall of the stator housing. The

block has a vertical wall 13 which, throughout its length, is in longitudinal continuation of the adjacent portion of the wall of the outlet passage from the pump. The 60 inner face of the block is curved forming a wall 14 that meets the wall 13 and thereby forms a sharp edge adjacent to the periphery of the rotor. The block is held in place in the stator housing by adjustable screws 65 15 that operate in slots 16 through the wall of the housing. Thus the block may be located in selected adjustments so that the edge thereof is spaced selected distances from the periphery of the rotor. This 70 block constitutes an adjustable baffle wall that prevents the liquid or other material drawn into the pump from passing in the space beyond the outlet opening and between the inner face of the housing and the 75 periphery of the rotor. Where the opening beyond the outlet opening from the stator housing and between the rotor and the stator is unobstructed there is an overthrow of material beyond the outlet opening which reduces the efficiency of the pump. The provision of the block baffling this space results in an increase in the efficiency of the apparatus.

The rotor of the pump is supported on a 80 power shaft 17, said shaft being mounted in external bearings 18 carried by I-beam brackets 19 supported on the members 1, and a bearing 20 carried by the stator housing. The shaft 17 passes through the stator 85 housing and has bolted to its inner end the hub 21 of the rotor.

The rotor is of known construction comprising a shell 22 in which is mounted a series of curved vanes 23. In order to take 90 up the space between the rotor shell and an end wall of the stator housing, thereby preventing vibration, an improved end thrust mounting for the shaft 7 is provided. This mounting comprises the bearing 20 that is 95 made up of two sections 24 and 25. The section 24 has an arcuate flange 26 and the section 25 has an arcuate flange 27 matched together as particularly shown in Fig. 6, said flanges having ears 28. A notched collar 29 is mounted on the shaft 17. The notched collar is associated with a collar 30 fast on the shaft 17, and interposed between the notched collar 29 and the collar 30 is a plurality of discs 31. The collar 29 is connected with the flanges 26 and 27 by adjustable draw bolts 32, so that by adjusting the 100 105 110

bolts 32 the collar 29 may be moved toward and away from the bearing 20. As the collar 29 is moved outwardly by the adjustment of the bolts 32 pressure is exerted on the discs which are forced against the collar 30, drawing the shaft outwardly taking up the space between the rotor and the stator.

The bearings for the shaft 17 are of special construction, the bearing 20 comprising a bearing housing 33 in which is mounted a journal bearing 34. The bearing housing 33 has a recess at its inner end in which is placed packing material 34. In the outer end of the bearing housing is a packing gland 36 with packing material 37 at the inner end of the gland. The gland is taken up by screws 38 which pass through the member 36 and into the end of the bearing housing. The bearings are of similar construction and all of the bearings have a special lubricating system which comprises oil cups 39 mounted in the top wall of the bearings and discharging through openings onto the top face of the shaft and a second set of oil cups 40, said oil cups 40 connecting into the lower bearing member, which lower bearing member has a series of branch passages 41, the openings of which lie against the under face of the shaft. The oil is fed by gravity in this manner against both the upper and lower faces of the shaft, effecting efficient lubrication of the shaft in the bearings.

The pump is equipped also with an ejector conduit 42 that enters the upper part of the stator housing, said ejector being controlled by a valve 43 for priming the pump.

It will be noted that the end plates or heads of the pump are so arranged that they

may be interchanged on the stator housing, 40 thus the pump may be made a right or left hand pump merely by reversing the end plates and reversing the position of the rotor blades.

I am aware that the invention may be 45 modified in certain particulars without departing from the spirit and scope thereof. I do not limit myself therefore to the exact details shown and described, but

What I claim and desire to secure by 50 Letters Patent is:—

1. A centrifugal pump comprising an approximately circular housing having an outlet passage, a rotor mounted in the housing and extending approximately to the 55 plane of the axis of said outlet passage, a block within the housing having a sharp edge extending toward the rotor adjacent to said outlet passage, and means for supporting said block in selected adjustments 60 to vary the distance of the sharp edge of said block from the periphery of the rotor.

2. A centrifugal pump comprising an approximately circular housing having an outlet passage and having slots through 65 the wall thereof at a distance from said passage, a rotor mounted within the housing, a block within the housing adjacent to said outlet passage having a sharp edge extending toward said rotor, and bolts extending through and being adjustable laterally in said slots and engaging and supporting said block, the positions of said bolts in said slots determining the distance of the sharp edge of said block from the periphery of 70 the rotor.

ALBERT W. ALBRECHT.
